[57] CLAIM

The ornamental design for a pump housing for a roller painting machine, as shown and described.

DESCRIPTION

FIG. 1 is an perspective view showing a pump housing, according to my new design.

FIG. 2 is a front elevational view thereof.

FIG. 3 is a rear elevational view thereof.

FIG. 4 is a bottom plan view thereof with the drip receiver portion omitted.

FIG. 5 is a top plan view thereof.

FIG. 6 is a right-hand side view thereof.

FIG. 7 is a left-hand side view thereof.

FIG. 8 is a bottom plan view thereof.

FIG. 9 is a section through the drip receiver portion taken at line 9—9 in FIG. 3 and viewed in the direction of the arrows and shown on an enlarged scale.
